DUPLEX ENVELOPE

Charles F. Pflanz, University City, Mo.

Application March 9, 1936, Serial No. 67,844

1 Claim. (Cl. 229—72)

My invention contemplates a duplex envelope consisting of a relatively small envelope container to hold a letter and a relatively large envelope container to hold printed matter, said containers being adapted to be connected together, and although subject to different postal rates, the smaller envelope being adapted to be enclosed within the larger envelope when transmitted through the mails in such manner that the small envelope may, if desired, be sealed against inspection and the large envelope remain unsealed.

Heretofore structures of this character have involved expensive preparation or expensive manipulation, or both, thereby necessitating an undue or excessive cost element which was objectionable in the utilization of duplex envelopes. The object of my invention, therefore, is to provide an improved construction and simple arrangement, whereby things which are subject to different postal rates and which are usually sent in separate envelopes or wrappers may be enclosed to all intents and purposes in practically one and the same envelope, so that the two things may not become separated and will arrive at their destination together.

Another object of my invention is to provide the small and large envelopes with window openings adapted to register with each other, which registration is easily accomplished prior to the joining of the two envelopes together. Such joinder may be done at any time prior to mailing, and with the assurance that a complete registration of the window openings will be had in a simple and efficient manner. By my arrangement, a duplex envelope may be produced at a minimum of expense and with a maximum of efficiency.

With the foregoing and other objects in view, the invention comprises the novel construction, combination, and arrangement of parts as hereinafter more specifically described and illustrated in the accompanying drawing, wherein is shown an embodiment of the invention, but it is to be understood that changes, variations, and modifications can be had which will come within the scope of the claim hereunto appended.

Fig. 1 is a front elevation of my duplex envelope, with a portion of the front wall broken away to show the construction.

Fig. 2 is a rear elevation of my duplex envelope showing the flaps of the large and small envelopes open, and the location of the small envelope in relation to the large envelope, part

of the rear wall being broken away to show the construction.

Fig. 3 is a rear elevation of the small envelope adapted to be contained in the large envelope.

Fig. 4 is an enlarged, vertical section taken on line 4—4 of Fig. 1.

As thus illustrated, the invention comprises an envelope 10 of any suitable form or character having one end or side thereof provided with a closure flap 11, said flap to be secured in place either by intucking or by the usual fastening device, or by any suitable means. The front wall of the envelope 10 is provided with a longitudinal window opening 12 of rectangular shape, which is preferably provided with a transparent slip 13, 15 or such transparency may be provided in any usual and well known manner, such as by treating the envelope with a preparation to render it transparent at the desired point. The purpose of providing the transparent slip in the envelope 10 at the rectangular opening 12 is to avoid a rough edge which might subject the outer envelope to a tearing action if said opening were not protected in this manner.

A small envelope 14, which may be of any 25 convenient size and shape, is provided with the usual flap 15 coated with the usual adhesive 16 at its outer edge. A rectangular window 17 is provided longitudinally in the rear face of the smaller envelope 14 and is preferably protected 30 by a transparent slip 18, or such transparency may be provided by the application of a preparation to the paper to render the same transparent in the usual and well known manner. The rectangular window 17 in the envelope 14 is adapted 35 to register with the rectangular window 12 in the envelope 10 when the two envelopes are joined together to make a duplex envelope. After the smaller envelope 14 is positioned within the envelope 10 as shown in Fig. 2, the envelope 14 40 may be secured to the front wall of the envelope 10 by a strip of adhesive 19 placed on the back of the envelope 14 at the upper portion of the rear wall of said envelope, and when attached to the front wall of the envelope 10 it appears as 45 shown in Fig. 1.

It will be understood, of course, that the utilization of the adhesive strip 19 is entirely discretionary, and the utilization of the transparent slip 18 in the envelope 14 is also discretionary. 50

The two envelopes 10 and 14 are brought together when it is desired to join the two in a duplex envelope, and the person manipulating the same adjusts the envelope 14 in the envelope 10 so as to cause the longitudinal, rectangular 55

window openings 12 and 17 to register, and then the adhesive strip 16 on the envelope 14 is moistened and said envelope secured by its flap 15 to the flap 11 of the envelope 10, and the duplex envelope is assembled ready for use. The first-class mail is placed in the envelope 14 with the name and address showing through the longitudinal, rectangular window opening 17, and by virtue of the registration of the window 17 in the envelope 14 with the longitudinal window 12 in the envelope 10, the name and address are discernible through both envelopes. If the adhesive strip 19 on the envelope 14 is to be employed, this strip is then moistened and the envelope 14 securely attached to the inner side of the front wall of the envelope 10, and thus the contents of the envelope 14 are closed against inspection. The other matter to be placed in the envelope 10 is then inserted so that said matter is between the envelope 14 and the rear wall of the envelope 10, thus holding said envelope 14 securely in position. The flap 11 may then be infolded or secured in any desired manner so that the contents of the envelope 10 may be subject to inspection.

It will be noted that by my construction the assembly of the duplex envelope may take place at the time the envelopes are being employed and just prior to mailing, or if desired these envelopes may be assembled in quantities and the first-class matter may be inserted in the envelope 14 by bending said envelope upwardly and outwardly from the envelope 10, and after the insertion of said first-class matter in said envelope 14 it is again returned to its position in the envelope 10, as shown in Fig. 2. By this arrange-

ment a duplex envelope is obtained requiring a minimum amount of manipulation both in preparation of the materials and the joinder of said materials in a composite envelope, and at a minimum of expense.

It is thought the many advantages of my improved duplex envelope in accordance with this invention can be readily understood, and although the preferred embodiment of the invention is as illustrated and described, yet it is to be understood that changes in the details of construction can be had which will fall within the scope of the invention as claimed.

I claim:

A duplex envelope comprising a relatively large rectangular compartment for printed matter requiring less than first-class postage, provided with a closure flap and a window on the same side as said closure flap, and a relatively small, rectangular letter compartment also provided with a closure flap, said latter closure flap being secured on the inside of the closure flap of said large compartment prior to closure of said large compartment, said small letter compartment having a window in one side thereof opposite the side to which the said closure flap is secured, said windows in both the large and small compartments registering with each other so that one address applied to the small compartment is sufficient for both kinds of mail matter, means for accessibly closing the large compartment, means for holding said small compartment against the inner front wall of the large compartment, substantially as described.
